UNITED STATES PATENT OFFICE.

MICHAEL M. DUDAS, OF CHICAGO, ILLINOIS.

DOOR LATCH.

Application filed July 17, 1925. Serial No. 44,325.

This invention relates to new and useful improvements in latches and more particularly to a latch designed for use on swinging doors for retaining the doors in a normally closed position. The main object of my invention is the provision of a pivoted latch member including a weight for normally retaining the latch member in a locking position and includes means for limiting the pivotal swinging movement of the latch in either direction.

Another object of the present invention is the provision of a latch of the above character having means whereby to lock the latch member in a locking position and whereby the same may be quickly and readily released when so desired.

With the above and other objects in view, my invention consists in the novel features of construction and the combination and arrangement of parts to be hereinafter more fully described, pointed out in the claim and shown in the accompanying drawings, in which:

Fig. 1 is a side elevation illustrating the application of the latch.

Fig. 2 is a detailed longitudinal sectional view of the latch.

Fig. 3 is a sectional view on the line 3—3 of Fig. 1.

Fig. 4 is a transverse section on the line 4—4 of Fig. 2, and

Fig. 5 is a front elevation of the pivotal latch with the catch member removed.

Referring more particularly to the drawing, the numeral 1 indicates a portion of a door casing having a swinging door 2 movable with respect thereto and attached to the door adjacent the casing is a base plate 3. Projecting downwardly from the plate 3 are the spaced arms 4 and 5 arranged in parallel relation as shown in Fig. 3 with their lower ends slightly curved as shown at 6. The plate 3 is removably attached to the door 2 by means of the screws 7.

The movable latch member 8 is pivotally mounted intermediate its ends upon the pin 9 the ends of which are mounted within suitable openings 10 formed in the lower ends of the spaced arms 4 and 5. At the inner end of the latch member which is movable upon the arms 4 and 5 and disposed at the lower side thereof is a weight 11 which normally retains the inner end of the catch member in a lowered position as

shown in Fig. 1, and the outer member in a raised or locking position. The outer end of the catch member is provided with a curved surface 12 which extends from the outer point of the latch member inwardly to the shoulder 13 which forms a stop for the stop bar 14, said stop bar engaging with the shoulder 13 to retain the door in a locked position.

The plate 3 is provided with a recess 15 in which is movable the lug 16 projecting from the inner end of the catch member 8, said lug being adapted to engage opposite ends of the recess 15 on the plate 3 for limiting the swinging movement of the catch member 8. In order to release the locking portion of the catch member from the stop bar 14, the flexible elements 17 are attached to the latch member at a point adjacent its outer end so that by pulling downwardly upon its flexible element, the shoulder 13 will be disengaged from the stop bar 14 for permitting opening movement of the door.

My improved locking feature for the latch member includes a U shaped member 18 one side of which extends thru both of the arms 4 and 5 and thru the slot 19 in the latch member 8 as is clearly shown in Fig. 3, the slot 19 being of sufficient size to permit swinging movement of the catch member 8 with the longer end of the member 18, (20) disposed therein. The catch member is provided with a transverse opening 21 arranged adjacent the slot 19 as shown in Figs. 2 and 3 adapted to receive the shorter end 22 of the locking member 18 when it is desired to lock the latch member as shown in Fig. 1. It will be apparent that in locking the latch member the member 18 is pushed inwardly from the position shown in Fig. 3 so that the shorter end of the member 18 is moved into the opening 21 and as the longer end 20 of the member 18 is disposed at one end of the slot, it will be impossible to impart a swinging or pivotal movement to the latch member for disengaging the shoulder 13 from the bar 14 so as to securely retain the latch member in a locked position.

It will be apparent from the foregoing that the latch member assumes a locking position, due to the weight 11 and when the door is swung to a closed position, the bevelled edge 23 on the lower end of the stop bar 14 will engage with the curved surface of the latch member and cause the latch

member to ride beneath the same until the stop bar drops behind the shoulder 13, and it will be understood that the weight 11 will be moved enough to always maintain the latch member in a locking position as shown in Fig. 1, during the time that the latch member is not engaged with the bar 14, the lug 16 normally retaining the latch member against additional movement so that the curved portion 12 of the latch member is always in position for engagement with the bevelled lower edge of the bar 14 and it will be apparent that either keeper or stop bars may be used in place of the member 14 as shown.

While I have shown and described the preferred form of my invention, it will be obvious that various changes in the details of construction and the combinations and proportions may be resorted to for successfully carrying my invention into practice without sacrificing any of the novel features or departing from the scope of the appended claim.

Having thus described my invention, 25
what I claim is:

The combination with a stationary structural unit, and a structural unit movable relative to the stationary structural unit, of a bracket secured to the movable unit and 30
having a recess formed therein and comprising spaced ears extending from the body of the bracket, a latch disposed between the spaced ears, said latch having an outer end portion provided with a shoulder, a stop bar 35
carried by the stationary unit and adapted to be engaged by the shoulder, a projection on said latch extending into said recess and cooperating with said member to limit pivotal movement of the latch, a weight on said 40
latch for normally retaining said latch in position to engage the stop bar, and a movable pin operable on said latch for releasably holding said latch in an inoperative 45
position with respect to the bar.

In testimony whereof I affix my signature.

MICHAEL M. DUDAS.
